[57] ABSTRACT

A shelf is adapted for rapid and easy mounting. The shelf platform has a contoured opening formed in its underside, into which is fit a member securable to a wall. After the member is secured to the wall, it is inserted into that contoured opening securing the shelf to the wall. A bracket can be attached to the underside of the shelf platform to more evenly distribute the shelf load.

RAPID MOUNTING SHELF

BACKGROUND OF THE INVENTION

The present invention relates to a shelf adapted for rapid and easy mounting.

At present there are many methods of mounting shelves on walls. In most, if not all, present methods of mounting a shelf to a wall, secured in either plaster or wood, an inordinate amount of effort is required.

A presently very popular method of shelf mounting entails the use of standards and brackets. Elongated standards are fastened at a plurality points to a wall, generally by means of screws. Brackets are then inserted into openings in the standards, which brackets are characterized by a top surface which is generally horizontal. To mount a single shelf two standards and two brackets are needed. The shelf is then placed upon the bracket top edges.

The drawbacks of the above system are obvious. To mount just one shelf, a plurality of time consuming steps are necessary. Two standards must be fastened to a wall with a minimum of two screws each. Brackets must then be placed in openings in each standard, both at an equal elevation. The brackets must then be secured to the standards within the openings. Lastly, the shelf is placed atop the brackets and in some instances, fastened to the brackets. As often happens, the standards are not equal elevation and, consequently, the shelf will not rest in a horizontal position.

In the above system the standard leaves unsightly marks on the wall if removed, and therefore, its removal leaves behind at least four screw holes plus the standard marks. Additionally, of major disadvantage in this system, is that the cost of the standards and brackets is often greater than the cost of the shelf.

Another method of shelf mounting involves brackets which have a rather wide top surface as well as side surface. The side surface is fastened to, and bears against, the wall. Generally, a screw is received in the bracket and is secured to the wall. Once the brackets are fastened to the wall the shelf is placed on their top surfaces, and where there is provision, fastened thereto. As in the case where standards are used, it is difficult and time consuming to secure these brackets at the same elevation; therefore, shelves mounted in this manner often hang at an unwanted angle.

The shelf of the instant invention is uniquely adapted for rapid and easy mounting. The mounting elements are inexpensive and the mount obtained is secure and dependable.

SUMMARY

It is a primary object of the present invention to provide a rapid and easy mounting shelf.

Another object of the present invention is the provision of a shelf, the mounting of which is secure and dependable.

In accordance with the present invention, the shelf platform has an elongated, trapezoidal slot formed in the underside thereof. An opening, contoured for the close reception of a fastening element is also formed in the shelf underside. The fastening element is secured to the wall and is received within the contoured opening. A bracket has a trapezoidal protrusion which is received within the trapezoidal slot and is angular so as to contact the wall. The shelf, thus described is quickly secured to the wall and held firmly in place.

These and other objects of the present invention will be apparent as the description continues.

DESCRIPTION OF THE DRAWINGS

5 FIG. 1, is perspective view of the underside of the shelf platform.

FIG. 2, is a perspective view of the securing element.

FIG. 3, is a perspective view of the bracket.

10 FIG. 4, is a perspective view of an alternative embodiment securing element.

FIG. 5, is a perspective view of the shelf assembled to the wall.

DETAILED DESCRIPTION

15 Referring to FIG. 1, there is illustrated the shelf platform 10 shown with its underside 12 facing upwards. That platform appears conventional except for the slot 14 which can be the product of a milling or other convenient operation. As shown in the preferred embodiment the slot 14 is elongated (extending across most of the width of the platform) and can be of trapezoidal cross section, the purpose of which will be apparent as the description continues.

20 As shown in FIG. 1, close to the shelf edge 18, there is formed the opening 20. That opening is contoured to receive therein the head 22 of the securing element 24 (FIG. 2). That element 24 may be designed in a plurality of shapes and sizes. As here shown it is characterized by a substantially cylindrical body 26 sandwiched between head 22 and tail 28 sections. The central bore 30 extends through the entire length of the element 24 and receives therethrough the nail 32 which is fastened to an upstanding member or wall. It should be obvious that a screw or toggle bolt etc., can replace the nail 32 30 as may be desired. Of further mention at this point is that the nail 32 can be of unitary construction with the securing element 24. That is, the central bore 30 can be omitted and the element 24 can have a unitary nail or screw formed at, and protruding from, the tail section 28. Element 24 is then driven into the wall until the tail section 30 contacted the wall.

25 In assembling the platform 10 to a wall, two securing elements 24, of the type hereinbefore described are secured to a wall at equal elevation. The platform 10 is turned and placed over the securing elements such that the head sections 22 fit into the contoured openings 20. The close reception of the head sections 22 into the openings 20 not only provides the vertical support needed for the platform but also inhibits any possible movement of the platform in the plane of said platform. It should be obvious that the length of the cylindrical section 26 should correspond to the distance between the opening 20 and the platform side 18. As such, the side 18 will be flush with the wall when the platform 10 is mounted. To bring the platform side 18 as close to the wall as possible, an recess (not shown) may be formed in side 18 adapted to receive the tail section 28 therein. Alternatively, the tail section 28 can be omitted altogether, such that the end of the cylindrical section 26 is flush with the platform side 18, which platform side will then be flush with the wall.

30 As indicated previously, the securing element 24 need not be designed with a tail section 28. In fact it need not be cylindrical. In FIG. 4, a securing element is shown as a flat trapezoidal section 24 with a large base 36 and a small base 38. A screw 40 (it can be a nail) is unitary with the small base 38 and the entire

unit is screwed into the wall by means of slot 42. A mating trapezoidal opening may be formed in the platform underside which receives therein the section 34. It should be obvious that when the base 38 is flush with the platform side 18 which in turn is flush the wall, the thickening of section 34 prevents horizontal movement of the platform 10.

The shelf as hereinbefore described will remain securely fastened to the wall if two securing elements 24 are used. However, it has been found advantageous to distribute the load of the platform 10 and its contents over a much larger weight bearing area so as to reduce stress. Additionally, it has been found of great advantage to transfer a portion of the vertical load on the wall to a horizontal load on the wall. As a result the shelf is provided with the bracket 42 shown best in FIG. 3. That bracket is characterized by a body section 44, a top section 46 in the shape of a trapezoidal protrusion, and a pressure bearing section 48. As shown, the body section 44 is disposed at an angle to the top section 46, but the pressure bearing section 48 is substantially perpendicular to the top section 46. Of note at this point, is that the top section 46 is dimensioned to be closely received within the slot 14. Before receiving the securing element 24 within the opening 20, the top section 46 is inserted within the slot that the pressure bearing section 48 faces platform side 18. The bracket is urged as far forward as it can go into the slot. The bracket 42 is designed such that when it is as far into the slot as it can go, the pressure surface 48 will be flush with platform side 18. As shown in FIG. 5, when the securing element 24 is received within the opening 20, the pressure surface 48 bears against the wall. In this manner a part of the weight of the platform and its contents is transferred from the securing elements 24 to the pressure surface 48. This load distribution reduces stress and provides for a secure mounting. As should be noted, when the bracket 42 is in its most forward position, bottom section 42 does not interfere with the opening 20.

Another embodiment of the present invention is worth mention. In some situations it may be desirable to produce a plate (not shown), fastenable to the underside of platform 10, which plate has formed therein the opening 20 and slot 14 such as hereinbefore described. Upon connecting the plate to the platform underside, the assemblage and use of the shelf is essentially as previously described.

As has been seen the present invention provides a rapid and easy mounting shelf. A minimum of effort

and inconvenience is attendant to the achievement of a stable and secure mounting.

It is obvious that the many changes may be made in the details of the instant invention without departing from the spirit and scope of the appended claims.

What is claimed is:

1. A shelf which comprises a weight bearing platform, a securing member adapted to be fastened to an upstanding structure, said platform having formed in the underside thereof an opening contoured to closely receive therein said member, said member of a shape which tends to restrict the movement of said platform along the plane of said platform (the shelf of claim 1 in which) said securing member being generally cylindrical comprising a widened head section adapted to be received within a widened section of said contoured opening, (whereby it restricts movement of said platform along the plane of said platform).
2. The shelf of claim 1 wherein said securing member is trapezoidal in shape, and adapted to be received within said contoured opening which is of compatible trapezoidal shape, whereby movement of said platform along the plane of said platform is restricted.
3. A shelf which comprises a weight bearing platform, a securing member adapted to be fastened to an upstanding structure, said platform having formed in the underside thereof an opening contoured to closely receive therein said securing member, said member and said opening of a shape which tends to restrict movement of said platform along the plane of said platform having a slot formed in the underside thereof, and a bracket securable to said platform within said opening, whereby upon assemblage of said member to said upstanding structure, said platform to said member, and said bracket within said slot, said member fits into said contoured opening firmly securing said platform to said upstanding structure and said bracket contacts said upstanding structure.
4. The shelf of claim 3 wherein said slot is elongated and trapezoidal in shape, the small base of which faces the platform underside, said bracket comprising a trapezoidal protrusion adapted to be closely received within said slot.
5. The shelf of claim 1 in which said member is generally cylindrical, comprising a widened head section adapted to be received within a widened section of said contoured opening, whereby movement of said platform along the plane of said platform is restricted.
